UNITED STATES PATENT OFFICE.

ELLWOOD F. BENNETT, OF BLANTON, FLORIDA.

ENGINE-STARTING-SWITCH EXTENSION ATTACHMENT.

Application filed January 24, 1928. Serial No 249,133.

Motor vehicles driven by an internal combustion power plant are generally equipped with mechanical starting means utilizing electricity as the motive fluid and including a foot operated switch in the starting circuit.

It has been found desirable and advantageous to operate the starter switch by hand from a point adjacent the usual instrument panel, hence the provision of an attachment that may be easily, quickly and economically applied to vehicles that are in use and upon the market without necessitating any change, or the drilling of openings, or the services of a skilled mechanic.

The invention relates to the provision of an attachment including a slip-on coupling for the starter button, a clamp for the instrument panel provided with a control, and adjustable connecting means between the said coupling and control, whereby movement of the control by hand actuates the usual starter button to close the starting circuit.

While the drawing illustrates a preferred embodiment of the invention, it is to be understood that in adapting the means to meet specific needs and requirements the design may be varied and such other changes in the minor details of construction may be resorted to within the scope of the invention as claimed without departing from the spirit thereof.

For a full understanding of the invention and the merits thereof, reference is to be had to the following description and the drawing hereto attached, in which,—

Figure 1 is a detail view illustrating the application of an embodiment of the invention.

Figure 2 is an enlarged sectional view of the end portion of the attachment adapted to be coupled to the starter button, the latter being indicated by the dotted lines.

Figure 3 is a detail perspective view of one form of clamp for connecting the attachment to a metal instrument panel having a straight flange.

Figure 4 is a side view of a modified form of clamp designed for an instrument panel having a curved flange.

Figure 5 is a detail perspective view of a form of clamp to be applied to an instrument panel of wood.

Figure 6 is a detail perspective view of a form of clamp to be applied to a bracket

forming connecting means between an instrument panel and the steering column.

Corresponding and like parts are referred to in the following description and designated in the several views of the drawing by like reference characters.

Figure 1 illustrates a cowl dash which is designated by the numeral 1. The numeral 2 denotes the usual inclined portion of the floor to which is fitted the button 3 of a starter switch. The instrument panel is designated by the numeral 4 and may be of metal or wood according to the make of vehicle.

The attachment comprises a coupling, a clamp, a control element pivoted to the clamp, a rod 5 forming connecting means between the control element and coupling, and a buckle 6. The numeral 7 designates the coupling which is preferably constructed of soft rubber and partakes of the nature of a cap to be slipped upon the starter button 3 and retained in place by frictional engagement therewith. The buckle 6 consists of an elongated body having a head 8 at one end which is embedded in the thickened end of the coupling 7 which is molded thereon. An opening 9 is formed in the body of the buckle 6 and extends through opposite sides thereof and provides for reception of an end portion of the rod 5. The end of the buckle body opposite the head 8 is formed with a threaded opening to receive the threaded end of the rod 5. A clamp nut 10 mounted upon the threaded end of the rod 5 secures it to the buckle in the required adjusted position. The control element 11 is pivoted to the clamp and is formed with an opening 12 through which an end of the rod 5 passes.

A pin 13 extending transversely through the rod 5 limits the movement of said rod with reference to the control element 11. The pin 13 functions as a stop. A piece of rubber 14 or like material is slipped upon the upper end of the rod 5 and is disposed between the pin 13 and the control element 11 and operates to prevent any noise or rattle. The upper rear end of the rod 5 is adapted to engage the control element 11 by a binding action, thereby limiting the movement thereof in one direction to normally maintain the parts in predetermined position.

The clamp to which the control element 11 is pivoted may be variously formed to suit the part to which it is to be attached. The clamp 15 illustrated in Figure 3 consists

of a spring clip comprising straight jaws to embrace the top and bottom sides of a straight flange projecting forwardly from the lower edge of a metal instrument panel. The clamp 16 outlined in Figure 4 consists of a spring clip having its jaws curved to conform to the curved flange along the lower edge of an instrument panel. The clamp 17 shown in Figure 5 comprises a plate and spaced upper standing jaws, one of the jaws being formed with a threaded opening to receive the clamp screw 18. This form of clamp is designed for a wooden panel. The clamp 19 appearing in Figure 6 of the drawings consists of a strip of metal having an end portion bent to embrace a bracket 20, a bolt 21 serving to connect the parts between which the bracket 20 passes. The clamp 19 is adapted for a motor vehicle in which the steering column is connected to the instrument panel by means of a bracket, as 20.

As is well known, the starter button is normally held projected by means of a spring and in accordance with the present invention the attachment is applied by slipping the coupling 7 over the projecting end of the button 3 and attaching the clamp to the instrument panel or other convenient part, as the bracket 20. The rod 5 is applied by slipping its upper end through the opening 12 of the control element 11, and by threading its lower end into the buckle 6, said rod being secured by turning the nut 10 to cause it to bind against the buckle 6. Pressure upon the control element 11 pushes the rod 5 forwardly and downwardly, thereby depressing the starter button 3 of the starting switch, whereby the circuit is closed in a manner well understood and the motor started. Upon releasing pressure from the element 11 the parts are returned to normal position by the usual spring cooperating with

the starter button 3, as will be readily appreciated.

Having thus described the invention, I claim:

1. A motor vehicle starter attachment comprising a control element, a clamp therefor forming means for attaching the said control to the vehicle, a coupling adapted to be fitted to the starter button, and a rod forming connecting means between the said control element and coupling.

2. A motor vehicle starter attachment comprising a pivoted control, a clamp therefor forming means for attaching the said control to the vehicle, a coupling adapted to be fitted to the starter button, a buckle attached to the said coupling, and a rod having screw thread connection with the buckle and a loose engagement with the said control element.

3. A motor vehicle starter attachment comprising a pivoted control, a clamp therefor forming means for attaching the said control to the vehicle, a coupling adapted to be fitted to the starter button, a buckle having an end portion molded within the coupling, and a connecting rod having an end portion threaded to the buckle and having its opposite end passing through an opening formed in the said control element.

4. A motor vehicle starter attachment comprising a buckle, a soft rubber coupling molded upon an end of the buckle and adapted to be slipped upon the starter button, a clamp, a control element pivoted to the clamp and formed with an opening, a connecting rod having an end portion passing through the opening of the control element and having its opposite end threaded into the said buckle, and a stop carried by the rod to engage the control element.

In testimony whereof I affix my signature.

ELLWOOD F. BENNETT. [L.S.]
